NARROW HEMMER ATTACHMENT FOR
SEWING MACHINESGeorge L. Hinman, New Haven, Conn., assignor
to The Greist Manufacturing Company, New
Haven, Conn., a corporation of Connecticut

Application October 7, 1936, Serial No. 104,431

5 Claims. (Cl. 112—143)

This invention relates to attachments for household sewing machines, and more particularly to an attachment designed to make a hem at the edge of a piece of material. In the particular modification of the invention illustrated in the drawing, the attachment is designed to make a relatively narrow hem, although it will be understood that the principles of the invention may be applied to devices for making hems of different 10 widths.

In devices of this character, and particularly in the field of so-called "narrow" hammers, some difficulty has been encountered in sewing or stitching the hem at the proper place to bind it 15 to the piece of material; that is, particularly in making a narrow hem upon the piece of goods, it sometimes occurs that the line of stitching will "run off" the hem entirely, so that the latter will not be stitched in place. This is often due to the 20 fact that the presser bar of the sewing machine with which the attachment is used is not correctly lined up with the needle bar, and in many cases where the alignment of these two parts is correct when the machine is first used, the presser bar becomes displaced or moved out of alignment in the use of the machine, so that when the 25 attachment is secured to such a displaced presser bar, the material will not be fed properly to the needle to bring the line of stitching properly upon 30 the hem. It will be noted that, as the point of attachment to the presser bar is at a considerable distance from the point at which the hem is turned, a slight displacement of the presser bar will effect a considerable displacement of the attachment at the point where the hem is turned.

One object of the present invention, therefore, is the provision of a hemmer attachment for sewing machines so constructed that it is capable of adjustment to bring the line of stitching or 40 sewing upon the proper place on the finished hem.

Another object of the invention is the provision of a hemmer attachment for sewing machines which is capable of a lateral adjustment to insure the proper feeding of the hem to the sewing 45 machine needle, and one in which said adjustment may be quickly and easily made without removing the attachment from the machine.

A still further object of the invention is the provision of a hemmer attachment of the character described, which may be of simple and economical construction and which, at the same time, will be efficient and positive in operation.

To these and other ends the invention consists in the novel features and combinations of parts 50 to be hereinafter described and claimed.

In the accompanying drawing:

Fig. 1 is a perspective view of a hemmer attachment for sewing machines embodying my improvements;

Fig. 2 is a plan view of the attachment; 5

Fig. 3 is a view similar to Fig. 2 showing the parts in an adjusted position; and

Fig. 4 is a sectional view on line 4—4 of Fig. 2.

To illustrate a preferred embodiment of my invention I have shown a hemmer attachment 10 comprising an attaching member or shank 10 having means comprising a bifurcated, laterally-turned portion 11 adapted to be secured to the presser bar (not shown) of the sewing machine, and a forwardly extending portion 12. To the 15 portion 12 of the attaching member is pivotally secured a foot 13 by the rivet 14. This rivet also passes through one end of a relatively thin sheet metal plate 15, which overlies the foot 13 and the, 20 inner end of which extends between the members 12 and 13. Below the head of the rivet 14 is a spring washer 16 designated to hold the parts against play in operation, but at the same time permitting movement of the foot 13 and plate 15 25 relatively to the part 12 about the rivet for a purpose to be hereinafter explained.

The plate 15 is slotted as at 17, and one arm of the plate is provided with a rearwardly pointing tongue 18 disposed within this slot. The other arm 19 of the plate 15 extends forwardly 30 over a corresponding part of the foot 13 (which, as will be understood, is also provided with a slot registering with the slot 17), and is provided with a downturned end 20 which bears against the edge of the material to serve as a guide to the 35 cloth to guide the latter properly to the hem turning mechanism, hereinafter described. Between this arm 19 and the underlying arm of the foot 13 is secured the base portion 21 of a scroll member 22, the scroll member being spirally 40 formed at its end and extending within the slot 17 to embrace the tongue 18, and serving to turn the cloth about the tongue 18 to form the hem and guide the hem to the sewing machine needle.

The plate 15 and underlying foot 13 are provided with registering slots, illustrated at 23, within which operates the needle of the machine in the usual manner. As shown in Fig. 4, a pin 24 is secured to the parts 13 and 15 in a position spaced laterally from the rivet 14, the head 24a of this pin standing in an opening 25 in the laterally extending portion 12 of the attaching member 10. The opening 25 is substantially larger than the head 24a of the pin, so that a pivotal movement of the parts 13 and 15 about the rivet 55

14 will be possible within limits permitted by the engagement of the pin head 24^a with the walls of the opening 25.

In Fig. 2 of the drawing, the foot and the parts 5 of the hemmer carried thereby are shown in an intermediate position in substantial alignment with the part 12, in which position the pin head 24^a is substantially centered in the opening 25. It will be understood that in the usual type of 10 sewing machine the material enters the hemmer from the left-hand side, as shown in this figure, the feed, of course, being longitudinally of the device, or from the bottom to the top, as here illustrated. If it is found that the stitch is running 15 off the hem so that the latter is not sewed in place, the foot 13, with associated parts, may be swung to the left, or from the position shown in Fig. 2 to the position shown in full lines in Fig. 3, which will in effect move the line of stitching 20 toward the right with relation to the hem, or closer to the edge of the goods, if, however, it is found that the stitching is too close to the edge of the goods when the device is set as shown in Fig. 2, and not close enough to the edge of the 25 hem, the foot may be moved to the right, or to the dotted line position shown in Fig. 3, which will have the effect of moving the line of stitching closer to the edge of the hem. It will also be true that moving the foot from the full line to the 30 dotted line positions in Fig. 3 will have the effect of making a slightly wider hem so that, while the present device is not primarily an adjustable hemmer, that is, adjustable for hems of various widths, it is capable of such an adjustment within 35 certain limits by moving the hem-forming mechanism from the full to the dotted line position shown in Fig. 3 of the drawing, or vice versa.

It will be obvious that there is provided by the invention illustrated a very simple and inexpensive hemmer attachment, which is capable of 40 being adjusted to effect the line of stitching at the proper place upon the hem, and also capable of being adjusted to effect a variation within limits of the width of the hem secured.

45 While I have shown and described a preferred embodiment of my invention, it will be understood that it is not to be limited to all of the details shown, but is capable of modification and variation within the spirit of the invention and 50 within the scope of the appended claims.

What I claim is:

1. A hemmer attachment for sewing machines comprising a shank having a horizontally disposed portion, a foot member pivotally secured to the lower face of said portion for pivotal movement with respect thereto, hem-turning mechanism carried by said foot member, said mechanism including a plate portion extending between said shank and foot members and there secured to the foot member. 5

2. A hemmer attachment for sewing machines 10 comprising a shank having a horizontally disposed portion, a foot member, means for pivotally securing said member to the lower face of said portion for pivotal movement with respect thereto, hem-turning mechanism carried by said 15 foot member, said mechanism including a plate portion extending between said shank and foot members and secured to the latter by said pivotal securing means.

3. In a sewing machine, a foot, a hem-turning 20 mechanism carried by said foot, means for attaching said foot to a sewing machine, means pivotally securing the foot to said attaching means for pivotal movement relatively thereto, means for limiting the relative movement of said 25 parts, and said securing means and said limiting means also serving to secure a part of said hem-turning mechanism to said foot.

4. A hemmer attachment for sewing machines comprising a shank member adapted to be attached to the presser bar of a sewing machine and having a horizontally disposed portion at its lower end, a foot member pivotally secured to said portion, hem-turning mechanism carried by said foot member, said mechanism comprising 35 a relatively thin sheet metal plate secured to the foot member and projecting forwardly therefrom and carrying hem-turning mechanism on its forward end. 30

5. A hemming attachment for sewing machines 40 comprising a foot part, a shank adapted to be secured to the presser bar of a sewing machine, means for pivotally attaching said foot part to said shank, a member secured to said foot part and extending forwardly therefrom, a hem-turning mechanism on the extended end of said member whereby said hem-turning mechanism is 45 pivotally adjustable relative to the presser bar to vary the width of the formed hem.

GEORGE L. HINMAN. 50
